DESIGN FOR A COCKTAIL SHAKER

Joseph M. Chernoff, New Britain, Conn.

Application April 6, 1935, Serial No. 56,251

Term of patent 3½ years

To all whom it may concern:

Be it known that I, Joseph M. Chernoff, a citizen of the United States, residing at New Britain, county of Hartford, and State of Connecticut, have invented a new, original, and ornamental Design for a Cocktail Shaker, of which the following is a specification, reference being had to the accompanying drawing, forming a part thereof.

I claim:

The ornamental design for a cocktail shaker as shown.

JOSEPH M. CHERNOFF.
